UNITED STATES PATENT OFFICE.

VITO A. QUAGLIANO, OF EAST BOSTON, MASSACHUSETTS.

DESIGN FOR A LENS OR SIMILAR ARTICLE.

60,106.

Specification for Design.

Patented Dec. 27, 1921.

Application filed April 13, 1921. Serial No. 461,107. Term of patent 14 years.

To all whom it may concern:

Be it known that I, VITO A. QUAGLIANO, a citizen of the United States of America, residing at East Boston, in the county of Suffolk and Commonwealth of Massachusetts, have invented a new, original, and ornamental Design for a Lens or Similar Article, of which the following is a specification, reference being had to the accompanying drawing, forming a part thereof.

In said drawings,

Figure 1 is a plan view of a lens showing my new design; and

Fig. 2 is an edge view thereof.

I claim:—

The ornamental design for a lens or similar article, substantially as shown.

Signed by me at Boston, in the county of Suffolk, and Commonwealth of Massachusetts, this eleventh day of April, 1921.

VITO A. QUAGLIANO.
